OVERSHOE AND PROCESS OF MAKING SAME

Filed Dec. 7, 1926

Patented Sept. 13, 1927.

1,642,305

UNITED STATES PATENT OFFICE.

GEORGE L. LAWRENCE, JR., OF MELROSE, MASSACHUSETTS.

OVERSHOE AND PROCESS OF MAKING SAME.

Application filed December 7, 1926. Serial No. 153,181.

My present invention is a novel and improved overshoe or gaiter, and includes a novel process of manufacturing the same.

An important object of the present invention is the provision of such an overshoe in which the vamp and quarter, or similar upper materials, overlap the foxing, or toe strip and heel piece. By means of this construction, viz,lapping the vamp and quarter over the foxing, a great saving in expense is effected, due principally to the reduction in the number of steps heretofore required in the manufacture of such overshoes or gaiters.

In carrying out my present novel process, I first draw the lining of the overshoe over a last, joining the same to the inner sole by cement. Next, the counter is applied. The next step in my novel process is the application of the foxing, or heel piece and toe strip. These heel pieces and toe strips may be of several forms, viz, a gum coated fabric, an all rubber foxing which may or may not be reinforced by a fabric strip on the vamp, and on the quarter if desired; or I may utilize a gum coated lining with or without a separate strip.

Subsequently, the quarter and vamp, or similar upper materials are applied, such quarter and vamp being so constructed and arranged as to lap over the aforesaid foxing, or toe strip and heel piece, being cemented thereto to secure a firm bond or union. The outsole is then applied, rolled, and the overshoe otherwise finished.

An overshoe constructed according to my novel process above briefly described, presents an appearance fully as neat as prior methods, and has the further advantage of being extremely economical to manufacture, presenting a saving of several cents for each pair of overshoes constructed according to my process.

I might also, if desired apply a fabric strip and rubber foxing separately,lapping the vamp and quarter over such composite strip. While this would be slightly more expensive than the process above described, it would still represent a considerable saving over the old constructions because of reducing the cost for cementing as well as the cost of application.

Numerous other modifications and variations of the individual parts, such as foxing constructions, will readily suggest themselves

to those skilled in the art, and I am not, therefore, in the present application, limiting myself to any particular form of foxing, so long as any foxing is utilized and the vamp and quarter or similar upper materials overlap such foxings, or toe strips and heel pieces.

I believe that an overshoe constructed as above described is novel, and I have therefore claimed the same broadly herein.

I also believe that my present process of overshoe manufacture is novel, and I have also claimed such process herein.

Further details of construction, advantages, and combinations, will be hereinafter more fully pointed out and claimed.

Referring to the drawings, illustrating a preferred embodiment of my present invention.

Fig. 1 is a side elevation of an overshoe lining, with the toe strip and heel piece attached;

Fig. 2 is a side elevation of the completed overshoe; and

Fig. 3 is a cross sectional view on the line 3—3 of Fig. 2.

Referring now to the drawings, Fig. 1 illustrates one stage in the construction of my novel overshoe. In this figure, the lining indicated generally at 1, has been applied to the last, and secured to the insole 2, as clearly shown in Fig. 3. The usual counter is also applied, but as this is usual construction, I have not illustrated the same herein. A toe strip 3 and heel piece 4 are then applied, joining or abutting at 5. This toe strip and heel piece may be formed in any suitable or desirable way. This may consist of a strip of fabric to which is applied a relatively thick coating of rubber, approximating in thickness the rubber foxings utilized in previous overshoe constructions. These pieces or strips would be applied to the overshoe after being previously united. These strips may also consist of an all rubber foxing, reinforced or not, as desired in the particular overshoe under construction, by a fabric strip on the vamp or quarter, or both. Or if desired I may utilize merely a gum coated vamp lining without a separate strip. The first two constructions above enumerated however, are preferable, although I do not wish to limit myself thereto.

After the application of such foxing or strips, the vamp 6 and quarter 7 are then ap-

plied. This vamp and quarter, or similar upper materials may be of any suitable fabric, such as cotton jersey, wool jersey, cashmereette, or the like. A quarter stay 8, preferably of rubber fabric is attached to the upper when same is assembled, and upon the upper being applied this stay 8 overlaps the foxings as clearly shown in the drawings.

As clearly shown in Figs. 2 and 3, the upper materials 6 and 7, or vamp and quarter, overlapping the foxing, as illustrated at 9, are cemented or otherwise secured to the outside upper rim or edge of said foxing. The outsole 10 is then applied, in the usual manner, extending upwardly and partially around the foxing 3 and 4, as illustrated at

11. The outsole is then rolled to produce the corrugations or design clearly illustrated in Fig. 2 and the overshoe otherwise completed.

20 While, in Fig. 3, I have illustrated the toe strip 3, or foxing, as a single strip or piece, this is merely a general showing, and is not intended to be limited to such a single strip, as I may desire to utilize any of the 25 forms of foxings described herein, such as gum coated fabric and the like.

While I have necessarily described my invention somewhat in detail, it will be appreciated that I am not limited thereto, but may 30 vary the size, shape and arrangement of parts within reasonably wide limits, without departing from the spirit of the invention.

My invention is further described and defined in the form of claims as follows:—

35 1. The improved process of manufacturing overshoes which consists in assembling lining materials and an inner-sole on a last, applying toe and heel foxing to said lining and inner-sole, applying a fabric vamp and quarter in such manner that the vamp overlaps said foxing and is secured thereto, applying an outsole, and completing the overshoе.

40 2. The improved process of manufacturing overshoes which consists in assembling lining materials and an inner-sole on a last, applying toe and heel foxing to said lining and inner-sole, applying a fabric vamp and quarter in such manner that the quarter overlaps said foxing and is secured thereto, applying an outsole, and completing the overshoе.

45 3. The improved process of manufacturing overshoes which consists in assembling lining materials and an inner-sole on a last, applying toe and heel foxing to said lining and inner-sole, applying a fabric vamp and quarter in such manner that the vamp and quarter overlap said foxing and are secured thereto, applying an outsole, and completing the overshoе.

50 4. The improved process of manufacturing overshoes which consists in assembling lining materials and an inner-sole on a last, applying toe and heel strips to said lining

and inner-sole, applying rubber foxing to said fabric strips, applying a fabric vamp and quarter in such manner that the vamp overlaps said foxing and is secured thereto, applying an outsole, and completing the overshoе.

5. The improved process of manufacturing overshoes which consists in assembling lining materials and an inner-sole on a last, applying toe and heel strips to said lining and inner-sole, applying rubber foxing to said fabric strips, applying a fabric vamp and quarter in such manner that the quarter overlaps said foxing and is secured thereto, applying an outsole, and completing the overshoе.

6. The improved process of manufacturing overshoes which consists in assembling lining materials and an inner-sole on a last, applying toe and heel strips to said lining and inner-sole, applying rubber foxing to said fabric strips, applying a fabric vamp and quarter in such manner that the vamp and quarter overlap said foxing and are secured thereto, applying an outsole, and completing the overshoе.

7. The improved process of manufacturing overshoes which consists in assembling lining materials and an inner-sole on a last, applying a fabric toe strip to said lining, then applying a rubber inner vamp, which said rubber vamp will also serve as a foxing, applying a foxing to the quarter portion of the overshoе, then applying a fabric vamp and quarter in such manner that the quarter and vamp will overlap and be secured to the foxings, applying an outsole, and completing the overshoе.

8. An improved overshoe of the kind described, comprising lining materials, inner-sole, foxing secured to said lining and inner-sole, and a fabric vamp and quarter, the fabric vamp overlapping the foxing, and an outsole.

9. An improved overshoe of the kind described, comprising lining materials, inner-sole, foxing secured to said lining and inner-sole, and a fabric vamp and quarter, the fabric quarter overlapping the foxing, and an outsole.

10. An improved overshoe of the kind described, comprising lining materials, inner-sole, foxing secured to said lining and inner-sole, and a fabric vamp and quarter, the fabric vamp and quarter overlapping the foxing, and an outsole.

11. An improved overshoe of the kind described, comprising lining materials, inner-sole, foxing secured to said lining and inner-sole, said foxing comprising a strip of fabric coated with rubber, and a fabric vamp and quarter, the fabric vamp and quarter overlapping the foxing, and an outsole.

12. An improved overshoe of the kind described, comprising lining materials, inner-

sole, foxing secured to said lining and inner-sole, said foxing comprising a strip of all rubber material, and a fabric vamp and quarter, the fabric vamp and quarter over-
5 lapping the foxing, and an outsole.

13. The improved process of manufacturing overshoes which consists in assembling lining materials and an inner-sole on a last, applying toe and heel foxings to said lining
10 and inner-sole, securing a quarter stay to a

fabric vamp and quarter, applying said fabric vamp, quarter and quarter stay in such manner that the vamp, quarter and quarter stay overlap and are secured to the foxings, the quarter stay concealing the joint between
15 the foxings, applying an outsole, and completing the overshoe.

In testimony whereof, I have signed my name to this specification.

GEORGE L. LAWRENCE, JR.
